PROCESS OF AND APPARATUS FOR DISTILLING OILS

Filed Oct. 9, 1919

Patented May 18, 1926.

1,585,224

UNITED STATES PATENT OFFICE.

CLIVE MORRIS ALEXANDER, OF NEW YORK, N.Y.

PROCESS OF AND APPARATUS FOR DISTILLING OILS.

Application filed October 9, 1919. Serial No. 329,624.

This invention relates to a process for distilling oil, and comprises a method of effecting a high degree of vaporization at a comparatively low temperature wherein an oil to be completely or partially vaporized is continuously transmitted through an externally heated retort or coil of pipe and during transmission is contacted with steam at a number of points whereby foam or films result, all the liquid and vapor phases being kept intimately in contact until the desired temperature is attained, then discharging the whole continuously into a separating chamber wherein the liquid and vapor phases are separated.

My invention also comprises a combination of elements including a length or coil of pipe, means for introducing steam at several points into the pipe, means for heating the pipe or coil externally, and a separating chamber.

In present day practice oils are vaporized in stills by the use of fire, steam, or combinations of the two. Light oils are vaporized with fire heating or steam heating, whichever may be desired. For crude oils or heavy oils, vaporization is generally effected by a combination of fire and steam, wherein the fire acts as an external heating agent, the steam being injected into the oil acting as a carrying agent.

In all these methods the oil vapors are removed from the liquid oil immediately they are formed. This procedure is wasteful of fuel and uneconomical quantities of steam are required for the vaporization of heavy distillates, due to the very low vapor tension of these heavy fractions. Where the heavy fractions from Mexican, California, or Gulf Coastal crudes are to be vaporized, high temperatures and large quantities of steam are required. If these heavy fractions are desired it is almost impossible to vaporize them without partial decomposition, which decomposition is to be avoided where heavy distillates are to be obtained for making lubricating oils. This is especially true with asphalt base oils, a natural undecomposed distillate being desired. Decomposition causes the formation of unsaturated bodies which render treating operations very difficult to obtain test oils. Furthermore, these test oils, when the decomposition products are not removed, change on standing, due to polymerization or oxidation.

When oils are distilled under conditions

whereby cracking decomposition results in the formation of unsaturated bodies these oils present difficulties in treating owing to emulsion formation. This emulsion formation is largely due to naphthenic acids formed by air oxidation of the oil while standing in tanks or by acid oxidation during treating in agitators. By distilling oil under non-cracking conditions as described in this improved process, the formation of emulsifying bodies is eliminated and non-emulsifying lubricating oils can thus be obtained.

In the present invention I charge the oil continuously into an externally heated length or coil of pipe and inject steam into contact with the oil at a number of points along its course of travel during heating, thereby causing a foam or film effect and so maintain all the liquid and vapor phases in intimate contact up to the point of discharge into the separating chamber. Since all the phases are kept in intimate contact up to the desired vaporization the mean vapor tension effect is utilized and as a result a higher degree of vaporization than can be obtained by present methods at the same temperature with an equal quantity of steam, is accomplished. Vaporization in a still, wherein the vapors are continuously removed as formed, utilizes only the fractional vapor tension, i. e., the liquid phase is in equilibrium with only the vapor phases in intimate contact therewith. By this new method, vaporization is effected as a whole followed by fractionation through condensation whereas in present day practice fractionation is effected through vaporization.

In a typical example of this process Mexican crude or say 20° Bé. gravity is charged continuously into the coil or length of pipe, fire heated from the outside. It has been found best not to inject steam into the oil before a point where the oil has reached a temperature of at least 250° F. and in some cases, depending on the oil and products desired, it is not necessary to contact the oil with steam before it has reached a temperature of 300° to 400° F. Heating the oil mentioned to 625° F. while contacting with steam will vaporize the oil to such an extent that a hard tar is obtained from the liquid phase after separating and cooling. No decomposition of the oil results under these conditions. If it were desired to obtain such a high degree of vaporization in an ordinary

still an uneconomical quantity of steam would be required and also it would be necessary to heat the oil to a temperature of 700° F. or more under which condition much decomposition would result. With California crudes from which heavy lubricating distillates are desired this method of vaporization through the use of the mean vapor tension is advantageous and effective 10 in avoiding decomposition.

After the desired vaporization has been attained through raising the temperature while maintaining the liquid and vapor phases in intimate contact, the whole is discharged into a separating chamber, where through expansion and centrifugal force the liquid and gaseous phases are separated. The liquid phase, generally a heavy tar, is drawn off continuously. The vapor phases 20 are conducted through towers and condensers wherein fractionation by condensation is accomplished. Instead of a centrifugal separator, other suitable types might be used.

A further modification of my invention 25 is to use several units like the one described but to operate these together so that only partial condensation is effected and utilizing the uncondensed vapors for contacting with the oil being heated in the next following 30 unit. For example, the crude oil to be vaporized is heated to the desired temperature while contacting with steam. The vapors of oil and water coming from the separator are subjected to partial cooling 35 such that only the heavy fractions are condensed. The light oil fractions and water which still remain in the vapor state are conducted to the next unit where they take 40 the place of fresh steam and are contacted with fresh crude being heated therein.

The mean vapor tension effect is present in this case as before but it is greater on account of the greater concentration of light 45 fractions. Since the mean vapor tension is greater the temperatures required for an equal vaporization in each successive unit are respectively lower. The lower the temperature necessary to effect the desired vaporization the greater the fuel economy 50 and the less the decomposition.

Another great advantage in working several units together is the economy in steam since steam addition to the first unit only is necessary. It also works well to do without the steam and contact with light oil 55 vapors only but not quite so effective. By so doing, it is necessary to run one unit without a contacting medium in order to produce light oil vapors for the following 60 units.

The accompanying drawing illustrates one form of apparatus for carrying out my invention.

Referring now to the drawing, 1 indicates a fire box, from which the gases pass

through channels 2, 3 and 4 defined by walls and partitions 5, the gases finally escaping through the opening 6. The passages 2, 3 and 4 may be made zigzag as shown. The gases pass from the passage 3 70 to the passage 4 through the opening 7. It is apparent that any number of such fire passages may be used, as desired.

Arranged to pass through the passages 4 and 3, is a length of pipe, one part of 75 which, numbered 8, passes downwardly through the passage 4, thence by a short connecting piece 9 it is connected to a portion 10 passing upwardly through the passage 3. This described length of pipe forms substantially an elongated still. The oil to be distilled is charged into this still from the charging line 11.

It should be noted that the hot gases pass 80 in one direction, while the oil flows in the opposite direction.

Steam is injected into the still at a plurality of points, preferably in that part of the still in which the oil is hottest, that is to say in the portion 10 of the still. This steam injecting means comprises a pipe 12 positioned on the inside of the still 10 which pipe is provided with a plurality of steam discharge openings 13. Steam is fed into the pipe 12 from the steam line 14.

Injecting steam by means of the apparatus shown violently agitates the oil and brings the liquid and vapor phases thereof into very intimate contact whereby the vaporization of the crude oil takes place very 100 rapidly.

While the sections of pipe forming the still are here shown as vertical and the fire passages also as vertical, it should be understood that the invention is not limited 105 thereto, but that the described parts may be horizontally or otherwise positioned, if desired.

The apparatus is so designed that the temperature of the oil in the branch 10 of the 110 still where it comes in contact with the steam is somewhere between 250 and 625° F. depending on the nature of the crude oil being distilled and on the amount of vaporization 115 desired. Branch 10 of the still is connected to a separator 15 of any desired design, which may be of the centrifugal type and which removes the tar from the distillate. The vapors from the separator 15 are led through a pipe 16 into the usual fractionating towers 17, from the bottom of which the heavy distillates may be collected and from which the light distillate vapors are led through a pipe 18. These light distillate 120 vapors may be collected in a condenser 19 or they may be led into a pipe 20 and then injected into a branch 10' of a second still of practically the same design as shown in Figure 1.

The second still is indicated on the right 125

hand side of the drawing and the corresponding parts of the two stills are indicated by corresponding reference characters.

In the second still the oil vapors from the fractionating towers of the first still are discharged from the pipe 20 into a pipe 12' and thence through openings 13' into the oil within the branch 10' of the still, whereby the oil in that branch is strongly agitated and the liquid and vapor phases thereof brought into intimate contact.

In other words, the injection of the oil and steam vapor into the second still takes the place of the injection of steam into the first still. If desired, however, steam from a steam line 14 may be passed into the pipe 12' and thence into the oil as in the first still, but usually this is not necessary.

The light distillate vapors leaving the fractionating towers 17 of the second still may be led to a third unit, not shown, where those vapors may be injected into the oil still in precisely the same manner that the light distillate vapors of the first still are used in the apparatus shown in Figure 2. The separators 15 may be provided with tar removal means 21. The fractionating towers may be provided with heavy distillate collecting means 22. Valves in the various pipes are indicated at 23.

The form of still shown may, of course, be varied widely within the scope of this invention. It should be understood that the invention may be modified in its various details as defined in the following claims.

It will be understood that the preliminary heating of the oil or a part of said preliminary heating contemplated by the present invention may take place prior to its admission into the pipe system 8, 9, 10, and that steam may be introduced otherwise than through the particular perforated pipe shown, provided that it is admitted in such a way as to subserve its function of sufficiently agitating the oil and provided further that the liquid and vapor phases are brought into intimate contact and maintained in such contact up to the maximum temperature employed.

I claim:

1. A process for non-destructive distillation of hydrocarbon oil comprising passing the oil in one direction through a zone where it is heated, injecting steam into the oil at a plurality of points along its passage through said zone and causing same to flow therethrough concurrently with the oil, maintaining the liquid and vapor phases present in intimate contact up to the point of separation, so as to raise the mean vapor tension, and separating the lighter and heavier fractions by fractional condensation.

2. A process for non-destructive distillation of hydrocarbon oil comprising passing the oil in one direction through a narrow

elongated still while being subjected to heat, injecting steam into the oil at a plurality of points along its passage through said elongated still to cause foaming and agitation of the oil and causing said steam to flow through said elongated still concurrently with the oil whereby the liquid and vapor phases are maintained in intimate contact while passing therethrough, and the mean vapor tension raised, and separating the vapors by fractional condensation.

3. A process for non-destructive distillation of hydrocarbon oil comprising passing it in one direction through a narrow elongated still while being subjected to heat, injecting oil vapor from a previous distilling operation into the oil at a plurality of points along its passage through said elongated still to cause foaming and agitation of the oil and causing said oil vapor to flow through said elongated still concurrently with the oil, whereby the liquid and vapor phases are maintained in intimate contact and the mean vapor tension raised, and separating the vapors by fractional condensation.

4. A process for non-destructive distillation of hydrocarbon oil, comprising preliminarily heating the oil, passing it through a narrow elongated still while being subjected to further heating, injecting oil vapor from a previous distilling operation and steam into the oil at a plurality of points while it is passing through said elongated still to cause foaming and agitation of the oil and concurrent flow of the liquid and vapor phases whereby the liquid and vapor phases are maintained in intimate contact while passing through said still and the mean vapor tension raised, and separating the vapors by fractional condensation.

5. A process for non-destructive distillation of hydrocarbon oil, comprising heating the oil, injecting vapor into said oil at a plurality of places, maintaining concurrent flow of the liquid and vapor phases, whereby to agitate said oil, keeping the liquid and vapor phases thereof in intimate contact so as to raise the mean vapor tension, separating the lighter and heavier fractions, and leading the lighter fractions to a second body of oil that is being heated and injecting said lighter fractions into said second body of oil, so as to agitate it and keep the liquid and vapor phases thereof in intimate contact and so raise the mean vapor tension.

6. A process of non-destructive distillation of hydrocarbon oil, comprising heating the oil, injecting steam into said oil at a plurality of places, maintaining concurrent flow of the liquid and vapor phases, whereby to agitate said oil, keeping the liquid and vapor phases thereof in intimate contact so as to raise the mean vapor ten-

- 6 sion, separating the lighter and heavier and vapor phases, whereby to agitate said 45 fractions, and leading the lighter fractions second body of oil and keep the liquid and to a second body of oil that is being heated vapor phases thereof in intimate contact, and injecting said lighter fractions into said and collecting the fractions from the said 50 second body of oil. 6
- 6 7. In an apparatus of the character de- 40 scribed, an elongated still through which oil is passed in one direction, means to heat said still externally, means to inject vapor 45 into the oil at a plurality of points along its passage through said still to flow there- through concurrently with the oil, where- 50 by the oil is agitated and the liquid and vapor phases maintained in intimate contact thereby raising the mean vapor ten- sion, and means to collect the distillates. 55
- 10 8. A process for non-destructive distilla- 40 tion of hydrocarbon oil, comprising heat- ing the oil, injecting vapor into said oil at a plurality of places in concurrent flow, whereby to agitate said oil and keep the liquid and vapor phases thereof in intimate 45 contact, separating the lighter and heavier fractions, and leading the lighter fractions to a second body of oil that has been pre- 50 liminarily heated and injecting said lighter fractions into said second body of oil while 55 it is subjected to further heating.
- 15 9. A process for non-destructive distilla- 40 tion of hydrocarbon oil, comprising heat- ing the oil, injecting steam into the oil at a plurality of points during the heating, 45 maintaining concurrent flow of the liquid and vapor phases during said heating whereby to agitate said oil and keep the liquid and vapor phases thereof in intimate 50 contact, separating the fractions, conduct- 55 ing the lighter fractions, while still in the vapor state, to a second body of oil that is being heated and injecting said vaporized lighter fractions into said second body of oil, maintaining concurrent flow of the liquid 60

- 10 10. In apparatus of the character de- 40 scribed, a still, means to heat said still, means to inject vapor into the oil in said still whereby to agitate the oil and bring the liquid and vapor phases thereof into 45 intimate contact, means to separate the lighter from the heavier distillates, a second still, means to heat said second still, means to lead the lighter distillate from the first 50 still and inject it into the oil in the second 55 still, whereby to agitate this oil and bring the liquid and vapor phases thereof into intimate contact, and means to collect the distillate from the second still. 60

In testimony whereof I affix my signa- 65 ture.

CLIVE MORRIS ALEXANDER.

- sion, separating the lighter and heavier fractions, and leading the lighter fractions to a second body of oil that is being heated and injecting said lighter fractions into said second body of oil, so as to agitate it and keep the liquid and vapor phases thereof in intimate contact and so raise the mean vapor tension. 7. A process for non-destructive distillation of hydrocarbon oil, comprising heating the oil, injecting vapor into said oil at a plurality of places in concurrent flow, whereby to agitate said oil and keep the liquid and vapor phases thereof in intimate contact, separating the lighter and heavier fractions, and leading the lighter fractions to a second body of oil that has been preliminarily heated and injecting said lighter fractions into said second body of oil while it is subjected to further heating. 8. A process for non-destructive distillation of hydrocarbon oil, comprising heating the oil, injecting steam into the oil at a plurality of points during the heating, maintaining concurrent flow of the liquid and vapor phases during said heating whereby to agitate said oil and keep the liquid and vapor phases thereof in intimate contact, separating the fractions, conducting the lighter fractions, while still in the vapor state, to a second body of oil that is being heated and injecting said vaporized lighter fractions into said second body of oil, maintaining concurrent flow of the liquid and vapor phases, whereby to agitate said second body of oil and keep the liquid and vapor phases thereof in intimate contact, and collecting the fractions from the said second body of oil. 9. In an apparatus of the character described, an elongated still through which oil is passed in one direction, means to heat said still externally, means to inject vapor into the oil at a plurality of points along its passage through said still to flow therethrough concurrently with the oil, whereby the oil is agitated and the liquid and vapor phases maintained in intimate contact thereby raising the mean vapor tension, and means to collect the distillates. 10. In apparatus of the character described, a still, means to heat said still, means to inject vapor into the oil in said still whereby to agitate the oil and bring the liquid and vapor phases thereof into intimate contact, means to separate the lighter from the heavier distillates, a second still, means to heat said second still, means to lead the lighter distillate from the first still and inject it into the oil in the second still, whereby to agitate this oil and bring the liquid and vapor phases thereof into intimate contact, and means to collect the distillate from the second still.

In testimony whereof I affix my signature.

CLIVE MORRIS ALEXANDER.
